UNITED STATES PATENT OFFICE.

JOSEPH BUSHY, OF PITTSBURG, PENNSYLVANIA.

HOSE-NOZZLE.

SPECIFICATION forming part of Letters Patent No. 721,665, dated March 3, 1903.

Application filed April 24, 1902. Serial No. 104,540. (No model.)

To all whom it may concern:

Be it known that I, JOSEPH BUSHY, a citizen of the United States, residing at Pittsburgh, in the county of Allegheny and State of Pennsylvania, have invented certain new and useful Improvements in Hose-Nozzles; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention has particular reference to certain improvements in that class of hose-nozzles for firemen's use constructed to throw both spray and solid streams; and it consists in certain peculiarities in the construction of parts and in certain novel combinations of elements, substantially as hereinafter described, and particularly pointed out in the subjoined claims.

25 A particular object of the invention is to provide a nozzle of simple, durable, and inexpensive construction having means by which it may be caused to throw a fine or a coarse spray at the will of the operator.

Another object of the invention is to provide a nozzle constructed to throw either a solid stream alone or both a spray and a solid stream at once and wherein the adjustment of the valve which controls the access of water to the spray-chamber is accompanied by 30 an adjustment of a spraying device which controls the outflow of the water from said chamber and causes it to be either in the form of a fine spray or in the form of a coarse spray at the will of the user.

35 These and other objects of the invention are accomplished by the construction illustrated in the accompanying drawings, in which—

Figure 1 is a longitudinal section through 45 a hose-nozzle containing my improvements, showing the position of the parts when water is shut off from both the passage for the solid stream and the spray-chamber. Fig. 2 is a similar view showing the position of the parts 50 when the passage for the solid stream is open and the spraying-chamber is closed. Fig. 3 is a similar view showing the extreme posi-

tion of adjustment of parts to open both the passage for the solid stream and the inlet to the spray-chamber. Fig. 4 is a detail side view of the tube through which the solid stream flows and its attached parts for controlling the spray. Fig. 5 is a detail view of the valve which controls the flow of water for the solid stream, together with a stem 55 and threaded piece, which are preferably employed as a part of the operating means therefor. Fig. 6 is a side view of the nozzle complete. Fig. 7 is a cross-section on the line 77 of Fig. 6. Fig. 8 is a detail view, partly in 60 section, of the means through which the solid stream issues from the nozzle and the parts secured thereto, showing a modified form of spraying device, the casing being in section and broken off near its front end. Fig. 9 is 65 a detail view looking at the rear end of Fig. 4 or Fig. 8.

The same numerals of reference designate the same parts in all the figures.

The casing of my improved hose-nozzle may 75 be composed of the front section 1 and the rear section 2, having a forwardly-extending reduced part 3, upon the forward end of which the rear end of said part 1 is threaded. Said front section 1 has an inwardly-extending 80 bevel or inclined forward extremity 4, and between its ends it is formed to provide an annular valve-seat 5. Located in the forward portion of said section 1 is a longitudinally-movable carrier 6, which for reasons 85 hereinafter stated is preferably in the form of a tube and the rear end of which is formed or provided with an annular valve 7, which controls the inlet of water to the spray-chamber 8. In order to guide the tube 6 in its movements, 90 it is preferably provided with longitudinal ribs 9, the outer edges of which engage the inner wall of the forward portion of the section 1. Said tube 6 carries an annular valve or device 10 at its forward portion, which has a circumferential bevel or inclination 11, which cooperates with the beveled or inclined forward end 4 of the section 1 to cause the water to issue from the spray-chamber 8 in a fine or a coarse spray, according to the position of 95 said valve or device relative to said end 4. The spray valve or device may be integral with the tube, as shown at 10^a, Fig. 8; but it is preferably threaded on said tube, as shown 100

in the other figures of the drawings, so as to be adjustable on said tube 6, and when the latter construction is employed the valve is preferably formed with a hexagonal or other angular end 12, adapted to be engaged by a spanner or other suitable wrench for convenience in adjusting it.

It will be observed that while the tube 6 is being adjusted to open or close the inlet to the spray-chamber the spray-valve 10 is similarly being adjusted toward and from the beveled front end 4 of the shell-tube 1. Thus by properly adjusting said tube 6 the water may be caused to issue from the spray-chamber in the form of a spray, which may be graduated as to fineness and force at the will of the operator simply by adjusting the tube 6. When the preferred construction of spray-valve 10 is employed, it may be adjusted independently of adjustment of the tube by screwing it forward or rearward on said tube, as is apparent.

The modified construction shown in Fig. 8 is intended especially to satisfy the desires of those who prefer a construction which throws a narrow instead of a wide spray.

I have shown the improvements hereinabove described embraced in a structure to which it is more especially adapted, wherein the nozzle is adapted to throw both a solid stream and a spray, and in said construction it is intended to utilize the part 6 not only as a carrier for the valves at both the inlet and outlet of the spray-chamber 8 and as the inner longitudinal wall of said chamber, but also to employ it to provide the passage through which the solid stream flows, and to this end it is made in the form of a tube, as shown, and the inlet to it is controlled by a valve 13, which seats against the rear extremity of said tube. The valve 13 herein shown is of that well-known type of pointed-cone valves which are placed concentrically in the nozzle-ajutage and adapted to be so operated in connection therewith as to cause the nozzle to throw a solid stream of any required volume, from nearly the full diameter of the discharge-opening to a small jet, without cutting off or diminishing the projectory force and pressure of water at the point of discharge from the nozzle. This type of valve is preferred by me. Preferably the valve 13 is adjusted to and from the tube 6 to close and open the passage through said tube.

For adjusting the valves and the tube 6 to cause the nozzle to throw either a solid stream alone or both a solid stream and a spray at once and to regulate the fineness of said spray I prefer the means shown in the drawings wherein the tube 6 is provided with two rearwardly-extending arms 18, the rear ends of which are connected by a cross-bar 19, having an opening 20, through which the stem 14 of the valve 13 loosely extends, and said valve-stem is formed rearward of said cross-bar 19 with a slot in which is fitted a cross-bar 15, having threaded ends which are

engaged by a threaded adjusting-sleeve 16, which when operated in one or the other direction will cause the threaded cross-bar to move longitudinally of the nozzle, and thereby cause or permit the valve 13 or the tube 6, or both said valve and tube, to be adjusted in a direction and to an extent which accords with the direction and extent of rotary movement given to said sleeve 16. For convenience in operating said sleeve it is preferably provided with ribs 16^a, whereby the grip of the fireman thereon is utilized to the fullest extent.

The sleeve 16, valve-stem 14, and cross-bar 15 are guided in their movements by the forwardly-extending reduced part 3 of the shell-section 2 and by a rib 21, with which said part 3 is formed, said rib extending longitudinally of the part 3 and having a central longitudinal opening 22 for the valve-stem and having longitudinal slots 23 at opposite sides of its central opening, which slots coincide with that in the valve-stem and also coincide with slots 24 in opposite sides of the wall of said part 3, as shown best in Fig. 7. The bottom of said rib has a depression 25, which forms a pocket to receive the stem 14 when the latter is in its lowermost position of adjustment. The adjusting-sleeve 16 encircles said part 3 and is permitted to have axial movement thereon in either forward or rearward direction, but is held against longitudinal movement.

When the parts are assembled, the valve-stem 14 extends through the opening 22 in the rib 21, and the cross-bar 15 projects laterally from both sides of said valve-stem and extends through the coinciding openings in said rib and the wall of said portion 3, which openings are of such length as to permit the cross-bar 15 to travel therein a distance equal to the extent of travel of said stem.

The parts are so positioned that the valve 13 has a movement relative to the valve 7 and cross-bar 19 a distance sufficient to open the inlet to the tube 6 without affecting the position of said valve 7, and it may be left in said position if it is not desired to use the spray. When said valve has moved said distance, its rear end has been brought into engagement with the cross-bar 19, and if it is desired to open the spray-chamber to the inflow of water thereinto the adjusting-sleeve 16 is given an additional turn or two, according to the character of spray it is intended to use, thus pulling the valve 13 farther rearward and causing it, by reason of its engagement with said cross-bar, to move the same and the tube 6 in the same direction, thereby opening the inlet to the spray-chamber and adjusting the spray-valve 10 toward the mouth 4. When the character of spray desired has been produced, further adjustment of the sleeve 16 is discontinued, and the parts will be held in position without necessitating provision of special means therefor. When the preferred form of the spray-valve 10 is

used and the inlet to the spray-chamber is open, the character of the spray may be changed without having to adjust any other part of the device, and consequently without 5 affecting any other part of the device by adjustment of said valve 10 on the tube.

During the initial movement of the valve 13 from its closing position (shown in Fig. 1) to the position shown in Fig. 2 the pressure 10 of inflowing water may be sufficient to hold the valve 7 to its seat; but in order to supplement the power of said water and to return the valve 7 to its seat when the valve 13 has been adjusted to permit the latter a 15 spring 26 is coiled around the valve-stem 14 and bears at one end upon the forward end of the cross-rib 21 and at the other end upon the rear surface of the cross-arm 19.

It will be observed that the tube 6 is so related to the forward shell part 1 as to form the spray-chamber 8, above mentioned, between the same, the outer wall of said chamber being formed by the inner wall of said shell part and the inner wall of said chamber 25 being formed by the outer wall of said tube, and that the seat for the valve 13, which controls the solid stream, is formed on said tube. By this means the construction of the device is reduced to the simplest possible form, and, 30 moreover, in the adjustment of the parts rearward to open the spray-chamber (from that shown in Fig. 2 to that shown in Fig. 3) and in the adjustment of said parts forward to close the spray-chamber (from that shown in 35 Fig. 3 to that shown in Fig. 2) the relative position of the valve 13 and its seat remains unchanged, as said tube, which carries said valve-seat, moves with the valve during said adjustment, and the movement of said valve 40 13 relative to said tube is confined to its adjustment, in which it opens and closes the inlet to said tube.

If desired, the tube 6 may serve as the nozzle-tip, as shown in most of the figures of the 45 drawings, or, if desired, a supplemental tip 30 may be screwed or otherwise secured thereto, as shown in Fig. 8.

The valve 13 is preferably threaded upon the forward end of its stem 14 for convenience 50 in assembling and disassembling the parts, as shown in Fig. 1.

Having thus described the invention, what I believe to be new, and desire to secure by Letters Patent, is—

55 1. A hose-nozzle, embracing in its construction a spray-chamber, having a valve-seat at its inner end, a carrier movable longitudinally in said chamber, said carrier being provided with a valve adjusted thereby to and from 60 said seat so as to control the inlet to said chamber, a spray-valve partaking of the movements of said carrier and adjusted thereby simultaneously with the first-mentioned valve, to control the spray issuing from said chamber, and means for adjusting said carrier.

65 2. A hose-nozzle, embracing in its construc-

tion a spray-chamber, having a valve-seat at its inner end, a carrier movable longitudinally in said chamber, said carrier being provided with a valve adjusted thereby to and from 70 said seat so as to control the inlet to said chamber, a spray-valve partaking of the movements of said carrier and adjusted thereby simultaneously with the first-mentioned valve, to control the spray issuing from said chamber, said spray-valve being adjustable relatively to said carrier, and means for adjusting said carrier.

3. A hose-nozzle for both solid stream and spray, embracing in its construction, a spray-chamber, a longitudinally - movable tube through which the solid stream flows, a valve partaking of the movements of said tube and controlling the inlet to said spray-chamber, a spray-valve also partaking of the movements 85 of said tube and controlling the outlet from said chamber, means for adjusting said tube, and a valve for closing the passage through said tube.

4. A hose-nozzle for both solid stream and spray, embracing in its construction, a spray-chamber, a longitudinally - movable tube through which the solid stream flows, a valve partaking of the movements of said tube and controlling the inlet to said spray-chamber, a 90 spray-valve also partaking of the movements of said tube and controlling the outlet from said chamber, said spray-valve being adjustable relatively to said tube, means for adjusting said tube, and a valve for closing the passage 95 through said tube.

5. A hose-nozzle for both solid stream and spray, embracing in its construction, a forward shell member having a valve-seat, a longitudinally-movable tube in said member of 105 such diameter relative thereto as to constitute therewith a spray-chamber forward of said valve-seat, said tube being adapted to permit the solid stream to flow through it, a valve partaking of the movements of said tube 110 and adjusted thereby to and from said seat to control the inlet to said chamber, a spray-valve also partaking of the movements of said tube and controlling the outlet from said chamber, means for adjusting said tube, and 115 a valve for closing the passage through said tube.

6. A hose-nozzle for both solid stream and spray, embracing in its construction, a spray-chamber having a valve-seat at its inlet end, a 120 longitudinally-movable tube therein through which the solid stream flows, said tube having an annular valve to engage said seat, and provided with devices rearward of said valve, a valve to control the inlet to said tube, said 125 valve being adjustable relatively to said tube throughout a portion of its whole extent of travel and adapted to engage said devices and thereby adjust the tube throughout the remainder of its travel, a spray-valve partaking 130 of the movements of said tube, and adjusting means for said tube and the several

valves, said adjusting means being connected with the stem of the valve which controls the inlet to said tube.

7. A hose-nozzle for both solid stream and spray, embracing in its construction a spray-chamber having a valve-seat at its inlet end, a longitudinally-movable tube therein through which the solid stream flows, said tube having an annular valve to engage said seat, and 10 provided with connected arms which extend rearward therefrom, a valve to control the inlet to said tube, said valve being adjustable relatively to said tube throughout a portion of its whole extent of travel and adapted to 15 engage the connection of said arms and thereby adjust the tube throughout the remainder of its travel, a stem projecting from the latter valve, a cross-bar extending through said stem and having threaded ends, an adjusting- 20 sleeve engaging the threaded ends of said cross-bar, and a spray-valve carried by said tube.

8. A hose-nozzle embracing in its construction a shell part having a beveled mouth, a 25 longitudinally-movable carrier therein so located with respect thereto as to provide a spray-chamber between the same, said carrier having a beveled device adjusted thereby relatively to the beveled forward end of said shell 30 part, a valve-seat at the inlet end of said spray-chamber, a valve carried by said carrier, and means for adjusting said carrier to thereby adjust said valve and device toward and from said valve-seat and beveled mouth 35 respectively.

9. A hose-nozzle for both solid stream and

spray, embracing in its construction a shell part having a beveled mouth, a longitudinally-movable tube through which the solid stream flows, said shell part and tube being 40 relatively arranged to provide a spray-chamber between the same, a valve partaking of the movements of said tube and controlling the inlet to said spray-chamber, a beveled device partaking of the movements of said tube 45 and adjusted thereby relatively to the beveled mouth of said shell part, means for adjusting said tube, and a valve for closing the passage through said tube.

10. A hose-nozzle for both solid stream and 50 spray, embracing in combination, a shell part, a longitudinally-movable tube therein so related thereto as to provide a spray-chamber between them, a valve carried by said tube, for controlling the inlet to said spray-chamber, a valve for controlling the inlet to said tube, adapted to seat in the inlet end thereof and having an initial rearward and a final forward movement relative thereto, means 55 connected with said tube and arranged in the path of said valve so that, in a part of the rearward movement of said valve, its seat and the first-mentioned valve will be caused to partake of its movement, for the purposes specified, and means for adjusting said valve. 65

In testimony whereof I affix my signature in presence of two witnesses.

JOSEPH BUSH.
